CLAIM

The ornamental design for a motorcycle breather, as shown and described.

DESCRIPTION

FIG. 1 is a perspective view of a motorcycle breather attached to a motorcycle engine, in phantom, for purposes of illustration only and forming no part of the claimed design, showing the new design.

FIG. 2 is an enlarged perspective view of the motorcycle breather of FIG. 1.

FIG. 3 is a front view thereof.

FIG. 4 is a bottom view of thereof.

FIG. 5 is a back view thereof.

FIG. 6 is a top view thereof.

FIG. 7 is an end view thereof, the opposite end being symmetrical; and,

FIG. 8 is an enlarged perspective view of a motorcycle breather showing an alternative embodiment of the new design, the back view thereof being identical to that shown in FIG. 5.
